UNITED STATES PATENT OFFICE.

JOHN MCMURDO, OF WINNIPEG, MANITOBA, CANADA.

GRAIN DOOR.

1,424,206.

Specification of Letters Patent. Patented Aug. 1, 1922.

Application filed March 14, 1921. Serial No. 452,378.

To all whom it may concern:

Be it known that I, JOHN MCMURDO, a subject of the King of Great Britain, and resident of the city of Winnipeg, in the 5 Province of Manitoba, Canada, have invented certain new and useful Improvements in Grain Doors, of which the following is the specification.

The invention relates to improvements in 10 grain doors as used on the standard type of grain car and an object of the invention is to provide a simply constructed and inexpensive appliance for fastening the door closed and to arrange the appliance so that 15 it can be readily locked or released as occasion demands and also to construct the appliance so that it can be readily fitted on the car.

With the above more important objects in 20 view the invention consists essentially in a pivoted and vertically shiftable wing located on one of the door posts and provided near the bottom with a catch shoulder, the post being apertured to receive the wing and 25 a locking plate countersunk in the door sill and provided with slots for receiving the lower end of the wing, the parts being arranged and constructed as hereinafter more particularly described and later pointed out 30 in the appended claims, reference being had to the accompanying drawings in which:—

Fig. 1 is an exterior view of a car fitted with my invention.

Fig. 2 is an interior view.

Fig. 3 is an enlarged detail horizontal sectional view through the door and adjoining posts.

Fig. 4 is an enlarged detail vertical sectional view through the door and looking 40 towards the wing.

Fig. 5 is a vertical sectional view at 5—5 Figure 4.

Fig. 6 is a perspective view of the locking plate.

45 In the drawings like characters of reference indicate corresponding parts in the several figures.

1 and 2 represent the customary door posts of a grain car, 3 the sill and 4 the upper 50 cross beam or lintel, such parts bounding the doorway opening 5. The door post 2 is provided with a vertical groove 6 adapted to receive one end of the grain door 7. In the present instance the groove is formed by ver-

tically channelling the post and facing it 55 with a metallic wearing plate 8 which has the inner edge lapped around the inner face of the post and suitably fastened thereto, the lapped portion of the plate preventing any possibility of nailing the door to the 60 post.

Here it is to be noticed that the metal faced channel so provided presents a vertically extending outer bearing wall 8' against which the end of the door is engaged 65 and an inclined wall 8'', the inclined wall allowing of the free escape of the latter end of the door when the other end is released as hereinafter described.

The post 1 is cut away to admit a vertically 70 extending pivot rod 9, the lower end of the rod being mounted in the sill whilst the upper end is mounted in the upper end of the recess formed in the post. On the rod I mount pivotally a wing 10 which in the present instance is formed from a comparatively stiff metallic plate having one edge curled or bent around the rod and the other edge extending tangentially from the rod. 75

The wing not only pivots on the rod but is 80 free so that it can slide a limited distance vertically and it is provided towards the lower end with a plate 11 whereby it can be raised with a crow bar or like tool.

On the sill beneath the wing I mount a 85 locking plate 12 which is countersunk in the sill so that the upper face thereof lies flush with the upper face of the sill. The plate is provided with a central opening 13 and two slots 14 and 15 communicating with the 90 opening and positioned at right angles to the same, the slot 15 passing lengthwise of the sill, whilst the slot 14 extends outwardly. The opening 13 is provided to receive the edge of the wing when the same is lowered 95 on the spindle or rod and the slots 15 and 14 receive the extending edge of the wing when it is in what might be termed the door locking and releasing positions respectively. Here I might explain that one end of the 100 door 7 is adapted to engage with the wing when the wing is extended in the slot 15, the arrangement being such that the said engaged end of the door is prevented from swinging outwardly by the locking of the wing in the slot 15. The inner face of the post 1 is provided with a protecting plate 16 which overhangs the edge of the door and 105

forms with the locked wing a vertical channel for receiving the said end of the door.

The post 1 is recessed to receive the wing when the same is turned outwardly, it being 5 desirable that the wing lie flush with the face of the post in such out-turned position.

When the door is placed in position the right hand end is inserted in the channel of 10 the post 2 and the left hand end is swung in against the plate 16, the wing at this time being turned outwardly flush with the post 1. Then the wing is raised to allow the lower 15 end thereof to pass out of the slot 14 and it is turned inwardly to engage the end of the door and is locked in this position by sliding it downwardly on the rod and into the recess 15.

After locking the door in this manner the grain is put into the car, it being of course 20 understood that the customary top door section (not shown) is used.

When it is desired to open the door a tool such as a crow bar is rested on the sill with 25 the end underneath the shoulder 11 and the outer end of the bar is forced down to pry up the wing and release it from the slot 15. This releases the door to swing outwardly under the pressure of the grain in the car, the freed wing being forced by the door outwardly against the face of the post, in which 30 position it will drop and lock itself in the slot 14.

From the above it will be obvious that this 35 invention can be readily applied on existing types of cars and without requiring much alteration thereof.

Further, the arrangement is an extremely 40 simple and inexpensive one and does not require a special door to be built, it being rather more of a fitting to the post than a part of the door structure.

Further, it forms a quick and positive lock 45 for the door and is so arranged that the door can be immediately released by the simple use of a crow bar or similar tool.

Whilst I have shown the special plate for 50 application on the door sill, I wish it to be understood that where sills are already protected by a wearing plate passing the full length of the sill the opening 13 and slots 14 and 15 could be formed in such plate.

What I claim as my invention is:—

1. In a grain car, the combination with a door post and a door, of means for releasably holding one end of the door against the 55 pressure of the grain within the car comprising a vertically disposed rod recessed within said post and extending from the door sill upwardly, a vertically disposed wing pivotally mounted on the rod and endwise shiftable thereon, a locking plate permanently mounted on the sill at the lower end of the wing and provided with a central opening and slots extending from the opening, the 60 said slots and opening being adapted to receive and lock the lower end of the wing against movement and in positions substantially at right angles one from the other and a plate located on the lower end of the wing. 65

2. In a car door fastening, the combination with a door post presenting an abutment for one side of the door of a wing connected to the post to cooperate with said abutment and hold said door in place and a member at one end of the wing presenting 70 angularly related channels in which the wing is selectively engageable, whereby the wing is adapted to be immovably held in operative or inoperative position, the connection between the wing and post permitting the wing to have the necessary movement for selectively engaging the same with the channels. 75

3. In a door fastening, the combination with a door post presenting an abutment engageable with one side of the door, of a wing adapted for engagement with the opposite side of the door, a vertical pivot rod connecting the wing to the post for swinging and endwise sliding movement, a plate at 80 the lower end of the pivot rod formed with angularly related slots with which the lower end of the wing is adapted to be engaged, whereby the wing may be immovably held either in operative or inoperative position. 85 90 95

Signed at Winnipeg, this 16th day of February, 1921.

JOHN McMURDO.

In the presence of—

GERALD S. ROXBURGH,
K. B. WAKEFIELD.
